UNITED STATES PATENT OFFICE

WILLIAM C. WOOD, OF EAST HAMPTON, CONNECTICUT, ASSIGNOR TO THE N. N. HILL
BRASS COMPANY, OF EAST HAMPTON, CONNECTICUT, A CORPORATION

BELL

Application filed November 8, 1930. Serial No. 494,278.

This invention relates to an improvement in bells and particularly to bicycle bells, the object of the invention being to produce a bell with a striker adapted to give a sharp blow to the bell so as to produce the desired ringing effect; and the invention consists in the construction as hereinafter described and particularly recited in the claims.

In the accompanying drawings:

10 Fig. 1 is a plan view of a bell constructed in accordance with my invention;

Fig. 2 is a sectional view on the line 2—2 of Fig. 1, enlarged;

15 Fig. 3 is a sectional view on the line 3—3 of Fig. 2;

Fig. 4 is a perspective view of the striker detached;

20 Fig. 5 is a perspective view of the striker-carrier and pinion, detached; and

Fig. 6 is an inside view of the bell detached.

In carrying out my invention, I employ a base 10 which, if used as a bicycle bell, will have one member 11 of a clip attached to it. Extending outward from the base is a post 12 upon which the gong 13 is mounted. This gong may be riveted to the outer end of the post or detachably connected therewith and, if desired and as shown, the inner end of the post may form the rivet for attaching the clip-member 11.

30 Mounted upon the post, within the base, is a pinion 14 and carried by this pinion is a yoke-like carrier 15 having upwardly-turned ends 16 formed with slots 17 for the passage through it of ends 18 and 19 of a longitudinally-movable striker 20, which is formed with a clearance-slot 21 through which the post extends.

35 Mounted in the base upon a stud 22 is a lever 23 having a finger-piece 24 formed at its inner end with a segmental rack 25 meshing with the pinion 14. The gong 13 is formed with a series of inwardly-turned projections 26 in line with the ends 18 and 19 of the striker. Movement of the lever 23 will turn the striker-carrier 15 and one end of the striker will engage with one of the projections 26 producing a sound and at the same time said projection throws the striker toward the opposite side of the gong so as to

produce a second sound. As this projected end comes in contact with the next projection, it will be thrown in the opposite direction so that a rapid series of strokes upon the gong will be produced.

55

I claim:

1. A bell comprising a base, a post mounted therein, a striker-carrier mounted on said post, a single longitudinally-movable striker supported by said carrier, a gong mounted on said post and adapted to be struck by either end of said striker, and means for turning said striker-carrier.

60

2. A bell comprising a base, a post centrally mounted therein, a gong mounted on said post and formed with a series of inward projections, a pinion mounted on said post, a striker-carrier mounted thereon, a longitudinally-movable striker supported by said holder and adapted to engage with said projections and to be moved longitudinally thereby, and means for rotating said striker-carrier.

65

3. A bell comprising a base, a centrally-arranged post mounted therein, a gong mounted on the outer end of said post and formed with inward projections, a pinion on said post, a lever having a segmental rack engaging with said pinion, a striker-carrier connected with said pinion and formed with up-turned slotted ends, and a striker having 80 ends extending through the slots in a carrier, and also formed with a clearance-slot for the post, and having its ends arranged in line with the projections in the gong.

70

In testimony whereof, I have signed this 85 specification.

WILLIAM C. WOOD.
